UNDERGARMENT FOR WOMEN

Nathan Bisberg, New York, N. Y., assignor to
Leona Undergarment Co. Inc., New York, N. Y.,
a corporation of New York

Application June 7, 1939, Serial No. 277,802

1 Claim. (Cl. 2—243)

My invention relates to improvements in an undergarment for women, popularly known as a slip. A slip is customarily worn beneath the outer garment or dress, to render the dress substantially opaque, to avoid contact of dress and body, and to give shape to the dress. A slip is a separate article of manufacture, which is made in various sizes, ready to wear, and is usually sold separate from the outer garment or dress. The slip when worn is required to be slightly shorter than the dress, so that when worn the slip is not seen. If it is longer than the dress, it produces an ungainly, slovenly and ill dressed appearance.

One object of the invention is to provide convenient adjustment of a slip whereby proper shortening to suit the outer garment or person may be accomplished by a person unskilled in the sewing art.

Another object of the invention is to provide a finished tailored edge in a slip at all times after shortening, without the need of resorting to sewing means at the time of shortening.

A further object of the invention is to provide such an edge as will not unravel or fray and withstand launderings.

A further object of the invention is to provide such simple adjustment means for a slip, as will not interfere with the manufacture of slips in accordance with the current art, and as will permit the manufacture of such slips substantially commercially as cheap as theretofore.

My invention also has for its objects such other advantages as hereinafter are made to appear.

To fully explain my invention, I shall briefly refer to the disadvantages, flowing from the shortening of a ready to wear slip, which it is the object of my invention to avoid.

In shortening a ready to wear slip, to suit the length of the outer garment with which it is to be worn, the wearer by cutting the bottom of the slip, simultaneously removes its stitched bottom hem or other tailored bottom edge, leaving an unfinished bottom edge which will unravel or fray in wearing and in laundering. To produce a new stitched hem or other tailored edge, requires the time and labor of a skilled person and access to sewing means, and this is so each time the slip is subsequently shortened. The inability, thus, to conveniently and quickly shorten a slip results in its non use or in its use with an unfinished untailored edge. There is, therefore, a definite need for an easily adjustable slip.

My invention is a slip which can be easily and in a few moments shortened to suit the length of the outer garment while at the same time without recourse to sewing means retaining its fit and a stitched hem or otherwise tailored bottom edge. It also permits a slip for a person of one height to be easily adjusted to a person of shorter height.

My invention consists in providing a slip with a plurality of narrow strips of cloth, said strips of cloth being sewed to or otherwise permanently applied by their upper edges to the outer surface of the slip, leaving the area between the upper and lower edge of each strip free, each strip encircling said slip completely and running parallel to the bottom edge thereof. The first of said strips so sewed or applied is preferably placed a short distance above the bottom edge of the slip and each of the balance of the plurality of strips follow similarly one above the other, each separately spaced and similarly permanently sewed or attached. It is preferable to use a sufficient number of strips to encircle an area approximating about $\frac{1}{6}$ of the length of the slip. Each of said strips is in fact a potential hem, narrow so that it may lay flat against the body of the slip, and not interfere with the contour of the outer garment. To shorten the slip, all that is necessary is to lift the free edge of that strip at which shortening is desired and to cut away beneath it close to its upper edge completely around the slip. To guide the cutting means, the body of the slip beneath each strip may be marked with a fine surface line or with a perforated line produced with a hem stitching machine, completely around the slip, but these means, however, are unnecessary since the slip body may be cut away safely without them. The result is a shortened slip, and the permanent strip from under which the slip has been cut away furnishes a finished tailored edge which will not unravel or fray and which will withstand many launderings. One strip in place of a plurality may be used, although impractical.

This way of providing an adjustable slip does not interfere with the manufacture of the body of the slip according to the best practice in the art. As heretofore the slip can be manufactured from cloth cut at a bias so that the warp and fill of the cloth is at an angle to the horizontal and vertical axis of the body to be clothed, giving resiliency and stretch to the cloth when needed and the other advantages inherent in cloth thus cut. As heretofore the body of the

slip may be designed and made with a plurality of cloth pieces to fit it to the contour of the body. The provision for shortening by my invention does not interfere with this practice, and furnishes an exceedingly inexpensive way of adjusting any type of slip while retaining a tailored edge and its other advantages. The manufacture of the improved slip remains substantially, commercially as cheap as heretofore, while the improved slip is by far more commercially attractive in that it is a tailored edged garment which retains its tailored edge even after shortening.

My invention also is in the combination and arrangement of parts and in the details of construction as herein set forth and claimed.

My invention is illustrated in the accompanying drawing in which:

Fig. 1 is an elevation of the improved slip in perspective.

Fig. 2 is an elevation of the lower portion of the improved slip in perspective to show a portion of the slip being cut away in the course of shortening.

Fig. 3 is an elevation of the improved slip in perspective after a portion of the slip has been cut away, showing the first strip as the new hem.

Fig. 4 is a detailed vertical sectional elevation taken on line 4-4, Figure 3, viewed in the direction of the arrow.

Fig. 5 is a detailed vertical sectional elevation taken on line 5-5, Fig. 1, viewed in the direction of the arrow.

Fig. 6 is an elevation view in perspective of one of the strips showing one portion of its free edge raised and other details.

Fig. 7 is an elevation in perspective of an improved slip showing a different type of slip body.

Similar numerals refer to similar parts throughout the several views.

Referring more particularly to the drawing, Figure 1 represents a slip, embodying my invention.

Upon the outer surface of the slip body 7, approximately 1 1/2" above its bottom edge 8, there is permanently attached in the manner herein-after indicated, a narrow strip of cloth of the same material and color, preferably, as that of the slip body 7. The strip continues completely around the slip body parallel to the bottom edge 8. In similar manner there is attached a plurality of such strips one above each other, each spaced approximately 1 1/2" apart. In my particular embodiment I have used strips 9, 10 and 11, although as many more may be used as are desired. Sufficient strips to cover approximately 1/6 the length of the hem produces a slip adjustable to the various dress lengths a wearer is apt to have, and one which may be adjusted to fit a shorter person.

The strips 9, 10 and 11 are made approximately 1 1/16" in width. In my embodiment these are made out of cloth strips 7/8" in width of the same material and color as the slip body, the strips being double stitched, after being fed through a hemmer device which folds the strip and reduces it to a finished edge strip of a final width of about 1 1/16". My invention, however, is not intended to be limited to the use of strip of this kind, but any equivalent strip with its edges finished will serve to attain the objects of my invention, whether made by hand or machine. The details on a large scale are shown for strip 9, in Fig. 6, which I have chosen as illustrative of all other strips.

In the embodiment of my invention these strips 9, 10 and 11 are attached to the outer slip body by sewing their upper edges 12, 13 and 14 to the slip body 7, leaving the portions of the strips below their upper edge down to and including their lower edges 15, 16 and 17 hanging free, as shown on Fig. 5 a vertical section of the slip on line 5-5 in Fig. 1. In sewing the upper edges of the strip to the slip body 7, I have preferably used a zigzag stitch 18, 19, 20, this stitch being unusually permanent, and not loosening or unravelling, by an accidental cutting across the stitch. I do not intend, however, to limit my invention by the type of stitch used, nor by the manner of attachment of the strips, any other means of secure attachment being sufficient provided the lower portion of the strip be free to act as a finished bottom edge after shortening. The manner of attachment by zigzag stitch 20, is shown on a large scale for strip 9 in Fig. 6, which I have chosen as illustrative of all strips.

To shorten a slip as desired, I proceed in the following manner. In Figure 2 the slip is shown being shortened. The bottom of strip 9, being free, is raised and with a scissor or other cutting means portion 21 of the slip body is cut away beneath strip 9 as close to the point of attachment of the strip 9 as will permit without cutting into the zigzag stitch. The commencement of the cutting is shown in Figure 6 at 26, where the strip is shown raised. This process is continued completely around the slip body until the entire slip is shortened. Figure 3 shows the shortening completed with strip 9 now serving as the new hem or tailored edge of the slip body. The cut edge of the slip body cannot be seen, being concealed beneath the new hem 9 as shown in Figure 4 a vertical section of the slip on line 4-4 in Figure 3. In similar manner the slip body may be further shortened permitting strip 10 and then strip 11 to successively serve as the tailored bottom edge of the slip. To guide the cutting means the body of the slip at point 26 in Figure 6, and beneath each strip at a corresponding point may be marked with a fine surface line or a perforated line produced with a hem stitching machine completely around the slip, but these means are, however, unnecessary since the slip body may be cut away safely without them.

The slip body shown in Figure 1 possesses the following features, but these are not intended to limit my invention to use with this type of slip body, it being equally well adapted to use with any type of slip body in which suitable shortening means, at the lower part of the slip body are a desirable feature. Thus, Figure 7 shows a half slip body 27 which terminates at its top, at the waistline, with an elastic band 28 to keep the slip in place. As shown it has side pieces of cloth F and G which are sewed in at these points to give fit to the waistline. It has the bottom edge 8 and strips 9, 10, 11, attached and constructed as described for Figure 1. The slip body as shown in Figure 1 is made of a front comprising a plurality of cloth pieces a, b, c, d, e, seamed together or in any other way, the front being seamed to a single piece of cloth comprising the back. The cloth is cut at a bias, in the manner heretofore stated, insuring to that slip the advantages flowing from the use of cloth thus cut. In the slip body the bottom edge 8 is made by folding under to produce a hem which is then permanently stitched. In Figure 1, a shoulder strap 22 is shown to support the body of the slip upon the shoulders, together with shortening means 24.

and 25 old in the art for procuring adjustment of the slip to fit about the upper portions of the body and for minor adjustment in length. Means 24 and 25 may be omitted without detracting from the invention. It is not intended, however, that my invention is to be limited to its use with a particular slip body possessing the above features, it being broadly adapted for use with any slip.

10 Various changes in the form, proportion and the details of construction may be resorted to without departing from the principle or sacrificing any of the advantages of this invention. Although I have described my invention with a certain degree of particularity, it is understood that the present disclosure has been made only by way of example.

Having thus described my invention, I claim:

15 A woman's undergarment having a finished bottom edge, a plurality of narrow fabric strips to serve as hems, each of said strips having a plurality of narrow fabric folds, longitudinal uncut edges, double stitched for permanently securing said folds together, said strips being disposed flat-

ly upon the outer surface of the undergarment body, circumferentially and parallel to its bottom edge, successively one above the other at short approximately equal intervals varying from about one-half (1/2) inch to two (2) inches, commencing 5 a short interval approximately one-half (1/2) inch to approximately two (2) inches above the bottom edge of said body, said strips being so disposed upon approximately the bottom one-sixth (1/6) portion of said body; and means comprising 10 a series of zigzag stitches for permanently securing the upper longitudinal edge of each strip to said undergarment body, the portion of each strip below said edge, hanging free; whereby a portion of said body may be severed by merely 15 cutting away said body beneath the strip at which shortening is desired, sufficiently to adjust it to the wearer and the outer dress with which it is to be worn, and whereby the strip beneath which the cutting takes place serves as a new finished 20 bottom edge for said body and to conceal the line of cut, substantially as described.

NATHAN BISBERG.
